US0D1031572S

(12) **United States Design Patent** (10) Patent No.: **US D1,031,572 S**
(45) Date of Patent: ** Jun. 18, 2024

(54) **FRONT PORTION OF A VEHICLE**

(71) Applicant: **FERRARI S.p.A.**, Modena (IT)

(72) Inventor: **Flavio Manzoni**, Modena (IT)

(73) Assignee: **FERRARI S.p.A.**, Modena (IT)

(**) Term: **15 Years**

(21) Appl. No.: **35/514,496**

(22) Filed: **May 11, 2022**

(80) **Hague Agreement Data**

Int. Filing Date: **May 11, 2022**

Int. Reg. No.: **DM/221321**

Int. Reg. Date: **May 11, 2022**

Int. Reg. Pub. Date: **Jun. 24, 2022**

(30) **Foreign Application Priority Data**

Nov. 12, 2021 (WO) WIPO110441

(51) LOC (14) Cl. **12-16**

(52) U.S. Cl.

USPC **D12/196**
